UNITED STATES PATENT OFFICE.

THEODORE G. KOHL, OF WAUSAU, WISCONSIN, ASSIGNOR TO THE ANKO MANUFACTURING COMPANY, OF WAUSAU, WISCONSIN, A CORPORATION OF WISCONSIN.

CHIMNEY CLEANER.

Application filed January 30, 1922. Serial No. 532,769.

To all whom it may concern:

Be it known that I, THEODORE G. KOHL, a citizen of the United States, residing at Wausau, in the county of Marathon and 5 State of Wisconsin, have invented certain new and useful Improvements in Chimney Cleaners, of which the following is a specification.

This invention relates to chimney cleaners 10 and particularly to chimney cleaners of the type described in Letters Patent No. 1,446,567, which were issued to me on February 27, 1923.

An object of my invention is to provide a 15 chimney cleaner in which the cleaning element is effectively maintained in contact with the chimney wall. A further object of the invention is to provide a chimney cleaner having an efficient form of cleaning 20 element.

These and other objects of my invention are attained in an embodiment of my invention which is illustrated in the accompanying drawings, in which—

25 Fig. 1 is a sectional elevation through a chimney equipped with the invention, and taken on line 1—1 of Fig. 2;

Fig. 2 is a vertical section at right angles to Fig. 1, and taken on line 2—2 of Fig. 1;

30 Fig. 3 is a horizontal section taken through the chimney on line 3—3 of Fig. 1; and

Fig. 4 is a fragmentary elevation similar 35 to Fig. 1, and showing the cleaning element in a different position.

In the drawings 1 indicates a chimney equipped with the invention, and provided with the customary lining 1', the usual inlets for pipes, only one pipe 2 however being shown, and with the usual soot collecting pan 3.

Between the lowest pipe 2 and the soot pan 3, the chimney is provided with an opening in which a supporting frame 4 is located. A shaft 5 which is loosely journaled in the frame 4 extends into the chimney and is provided on its outer end with a hand crank 6. Within the frame 4 the shaft 5 has mounted thereon a collar 7 having a 45 rounded face 8, and said collar is provided with a set screw 9 for clamping the same to the shaft 5 to properly position it in the frame 4. The inner end of shaft 5 is provided with a yielding bearing 10, which 50 bearing consists of a plurality of turns of

heavy steel or other resilient wire. To provide greater resiliency each end of the wire is formed with coils 11 between the bearing proper and the points of attachment to the frame 4. 60

The inner end of the shaft 5 has fixed thereto a sprocket 12 which is located at the center of the chimney. At the upper end of the chimney a rod 13 carries a flanged pulley 14 which is supported above and has substantially the same diameter as the sprocket 12. An endless band or chain 15 passes over the sprocket 12 and pulley 13 and carries a channel member 16 to which the cleaning member is attached. Supporting plates 17 65 between which the scrapers are clamped are attached to the channel member 16 by means of straps 18 which are bent up from the plates. A strap 19 which is clamped between the member 16 and the straps 18 extends inwardly to clear the end of rod 13 and is then bent over at right angles and into a plane parallel to the plane of the two falls of the chain 15. The strap 19 is provided with a 70 pivot pin 20, the axis of which lies in the plane passing through the axes of sprocket 12 and pulley 13. Connected to the pivot 20 is an arm 21 which carries a horizontal extension 22 at its lower end, and this extension or chain guide is provided with openings through which the falls of the chain 15 pass. 75

The cleaning element comprises a plurality of scraper plates 23 which are clamped between the plates 17. The outer edges of the plates 23 are cut at an angle of about 45° to divide the plate into a plurality of narrow scraper blades 34. These straight cuts extend inwardly about half way from the edge of the scraper plate to supporting 80 plates 17. Curved slots extend back from the ends of these straight cuts to approximately the edge of the supporting plates 17. This construction provides a plurality of scraper blades each of which is connected to the supporting means at a point offset from a line normal to the chimney wall at the point of contact therewith; the outer end of the blade having parallel sides which meet the wall at an angle and the inner end of the blades being of less area, and consequently more flexible, than the outer end. 85

As shown in Fig. 3, the device is installed in a square chimney but it is obvious that the device may be used with chimneys hav- 90

ing cross-sections which are rectangular, circular or oval. That the construction may be clearly shown in this view, the top plates 23 have been somewhat shortened, thereby 5 leaving open spaces at opposite sides of the brush but it is obvious that these plates 23 may be extended to provide narrow scraper blades which contact with a full one-half of the periphery of the chimney wall.

10 When installed the length of the chain 15 is so adjusted that the inner end of the shaft 5 is somewhat higher than the outer end, thereby setting up a stress in the coils 11 of the bearing 10. When the heated 15 products of combustion enter the chimney the chain will expand but the yielding bearing 10 will take up the slack produced by expansion of the chain.

The chain guide 22 and the associated 20 elements cooperate to hold the cleaning member normal to the chimney walls since the opposite falls of the chain hold the guide 22 horizontal and the arm 21 vertical. The pivot pin 20 which is carried on the scraper 25 supporting plates is thereby held in the plane of the axes of the sprocket and pulley and prevents tilting of the scraper out of the horizontal. In case slack should occur 30 in one or both falls of the chain, the guide will aid in keeping the falls from becoming entangled.

The cleaning member is normally kept 35 at its lowest point and to clean the chimney the crank 6 is operated to carry the scrapers up one side of the chimney, then over the pulley 13 as shown in Fig. 4, and down the other side.

The particular shape of the scraper blades 40 makes the cleaner very efficient in the removal of soot deposits and renders it free from clogging by soot which is removed. Due to the more flexible portion at the rear of the blades and to the fact that the ends of the blades are offset from their points 45 of support, a blade will readily tilt about that corner of the blade which is nearest the support, thereby opening up spaces between the blades through which the loose material may pass.

50 It is to be understood that my invention is not limited to the specific embodiment herein described since without departing from the spirit of my invention, many changes may be made in various elements, 55 and in the relative size, shape and locations of the same.

I claim:—

1. A flue cleaner comprising rotatable means located centrally of and near the 60 opposite ends of a flue, an endless band passing over said rotatable means and having two substantially parallel strands, means for moving said band, a cleaning element attached to said band, a guide contacting 65 with both strands of said band, and means

including a pivot located in the plane passing through the axes of said rotatable means for connecting said cleaning element and said guide.

2. A chimney cleaner comprising a pulley 70 located centrally of a chimney near the upper end thereof, a band supported on said pulley and having two substantially vertical falls depending therefrom, means for moving said band, a cleaning element attached 75 to said band, a guide contacting with both falls of said band and means for connecting said cleaning element and said guide.

3. A chimney cleaner comprising a pulley 80 located centrally of a chimney and near one end thereof, a band supported on said pulley and having two substantially vertical falls depending therefrom, means for moving said band, a cleaning element attached to 85 said band, a supporting guide contacting with said band, and means connecting said cleaning element and said supporting guide and permitting said cleaning element to pass over said pulley.

4. A chimney cleaner comprising a pulley 90 located centrally of a chimney near the upper end thereof, a band supported on said pulley and having two substantially vertical falls depending therefrom, a cleaning element carried by said band, means for moving said band, a guide contacting with both falls of said band and means including a pivot located in the vertical plane passing through the axis of said pulley for connecting 95 said cleaning element and said guide.

5. A chimney cleaner comprising a pulley 100 located centrally of a chimney near the upper end thereof, a band supported on said pulley and having two substantially vertical falls depending therefrom, means for moving said band, a cleaning element attached to 105 said band, a guide plate in contact with both falls of said band, an upwardly extending arm on said guide plate and means including a pivot located in the vertical plane 110 passing through the axis of the said pulley for connecting said cleaning element and said guide plate.

6. A chimney cleaner comprising a pulley 115 located centrally of a chimney near the upper end thereof, a band supported on said pulley and having two substantially vertical falls depending therefrom, means for moving said band, a cleaning element attached to 120 said band, a strap carried by said cleaning element, a guide contacting with both falls of said band and means including a pivot located in the vertical plane passing through the axis of said pulley for connecting 125 said strap and said guide.

7. A chimney cleaner comprising a pulley 130 located centrally of and near the top of the chimney, a band supported by said pulley and having two substantially parallel falls, means for moving said band and a cleaning

element carried by said band and having a scraper plate contacting with said chimney walls, the outer edge of said plate being divided into a plurality of scraper blades by 5 parallel cuts which extend from and diagonally to the edge of the plate.

8. In a chimney cleaner, a movable band having parallel falls located in a chimney, a cleaning element carried by said band, said 10 element comprising a plurality of scraper blades lying substantially in a plane normal to the chimney walls and having parallel side edges disposed diagonally to said walls.

9. In a chimney cleaner, a metal scraper 15 blade comprising a narrow strip having an outer end face adapted to contact with a chimney wall, the sides of said strip adjacent the outer end extending diagonally to the end face and the sides of said strip inwardly of said strip 20 wardly of said diagonally extending portions being arcuate.

10. In a chimney cleaner, a metal scraper blade comprising a narrow strip having an outer end face adapted to contact with a chimney wall, the sides of said strip adjacent the outer end being parallel and extending diagonally to the end face and the sides of said strip inwardly of said parallel portions being arcuate. 25

11. In a chimney cleaner, a flat scraper 30 blade comprising an inner end portion adapted to be attached to a moving means, an outer portion having an end face adapted to contact with a chimney wall and having parallel sides which extend diagonally to 35 said end face and an intermediate portion of less cross-sectional area than said outer portion connecting said inner and outer portions.

In testimony whereof I affix my signature.

THEODORE G. KOHL.
